UNITED STATES PATENT OFFICE.

FREDERICK J. COTA, OF MENOMINEE, MICHIGAN.

MANIFOLDING TABLET OR BOOK.

SPECIFICATION forming part of Letters Patent No. 738,413, dated September 8, 1903.

Application filed November 15, 1902. Serial No. 131,539. (No model.)

To all whom it may concern:

Be it known that I, FREDERICK J. COTA, a citizen of the United States, residing at Menominee, in the county of Menominee and 5 State of Michigan, have invented a new and useful Manifolding Tablet or Book, of which the following is a specification.

My invention is an improvement in manifolding-books, and relates especially to account-books used with credit customers, the object being to provide a book in which an entry will be duplicated upon an under sheet by means of an intermediate carbon-sheet; and a further object is to provide a book 15 whereby the account of each customer is kept separately and in duplicate, the merchant holding the original entries bound in book form and the customer holding the detached leaves, each containing an itemized statement 20 of the amount purchased at the time the entry was made or of the amount paid, if a payment was made, and in either case showing the full amount due and unpaid provided there is an unpaid balance. In this manner 25 the chances of error from the confusing of accounts of various customers or from failure to have the entries on the merchant's book agree with those on the memoranda given the customer are reduced to a minimum.

30 In the accompanying drawings, Figure 1 is a view of my improved book closed. Fig. 2 is a view of the book, the covers being open, the carbon-sheet being in position for use. Fig. 3 is a view showing the book partly 35 closed, the carbon-sheet lying directly under its protective cover. Fig. 4 is a side elevation, the book being closed. Fig. 5 is a detail of construction.

In the drawings, A represents a continuous 40 flexible back, preferably formed of a tough substantially stiff paper.

B is an oblong book formed of a plurality of leaves, to be described hereinafter.

The sheet A is bent to form three portions 45 A', A², and A³, the portions A' A² being longer than the portion A³.

The book B has a flexible binding B', extending but a short distance from the bound edges of the leaves. The book is laid upon the section A² with the binding B' adjacent the portion A'. Metal fasteners B² are then driven through the binding B', the leaves of the book,

and the portion A² and clamped or clenched on the outer side of A². The leaves of which the book is formed are preferably of different colors or of tinted leaves alternating with white leaves. The first and every alternate leaf bears the words "Name," "Date," "Book No.—" at the top, with sufficient space following them to permit the name of the customer, date of transaction, and number of the book to be inserted. Below this heading the leaves are properly ruled by horizontal and vertical lines, the horizontal lines being numbered on the left-hand side of the page and 60 having two vertical columns on the right, one being for the itemized statement of the transaction of even date with the date at the top of the page and the other for a summary of the aggregate of any amounts due from previous 65 transactions. The tinted or colored sheets are divided adjacent their bound edges by lines of weakness B³, (shown in Fig. 3,) the upper permanent page being removed in order to show same. A carbon-sheet C is permanently secured at one end to the portion A² and 70 is adapted to lie on the portion A², the back of the carbon resting against A³, and when the book is closed the face of the carbon will rest on the leaves of the book. It will be particularly noted that when the completed book is 75 opened the leaves of the book fold back in one direction and the carbon-leaf in the opposite direction.

In use the carbon is folded under the ruled 85 leaf, resting face down on the tinted leaf, and any entry made on the top leaf is necessarily transferred to the tinted leaf, which is then torn out along the lines of weakness and handed the customer, whose name is inserted at the top of each permanent page. It 90 will be noted that the carbon cannot be placed so as to transfer the account to the back of the permanent leaf, no matter how hurried the merchant may be, as is often the 95 case when loose carbon-sheets are used. When the entry has been made, the carbon-sheet is thrown back, and as it folds back in a direction away from the lines of weakness there is no danger of tearing the carbon-sheet 100 in detaching the duplicate entry for the customer. When the book is folded, the carbon is folded back under the portion A³, which serves as a protector for the carbon-

sheet, so that when the book is opened there is no danger of catching and tearing the carbon by drawing it back with the outer covering A', which covering folds over the portion A³.

It is understood, of course, that one of these books is used for each customer with whom an account is kept.

Having thus fully described my invention, 10 what I claim as new, and desire to secure by Letters Patent, is—

1. In a book of the kind described, the combination with a continuous flexible cover, of a blank-book inclosed by said cover and 15 adapted to fold back over one end of said cover, and a carbon-sheet permanently se-

cured to the cover beneath the free edges of the book and adapted to be folded over the leaves of the book and to be opened in a direction opposite to the direction in which the 20 book is opened.

2. In a book of the kind described, the combination with a flexible cover bent into three portions, of an account-book resting on and secured to the middle portion, and a carbon-sheet permanently secured to the middle portion beneath the free edges of the book and adapted to fold over the said edges. 25

FRED. COTA.
